(57) **CLAIM**

The ornamental design for a combined monitor display and disc player, as shown.

DESCRIPTION

FIG. 1 is a front elevational view of a combined monitor display and disc player showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof;

FIG. 8 is a reference cross-sectional view thereof, taken along the line VIII—VIII in a direction of arrows shown in FIG. 1 wherein inner mechanical details are omitted; and, FIG. 9 is a reference right side elevational view thereof in the open position.
